UNITED STATES PATENT OFFICE.

ZOLTAN B. CSIKY, JACOB KRONHEIM, AND ZOLTAN TAMASSY, OF CLEVELAND, OHIO;
SAID TAMASSY ASSIGNOR TO SAID KRONHEIM.

CONVERTIBLE CHAIR.

951,211.

Specification of Letters Patent.

Patented Mar. 8, 1910.

Application filed March 31, 1909. Serial No. 487,014.

To all whom it may concern:

Be it known that we, ZOLTAN B. CSIKY, JACOB KRONHEIM, and ZOLTAN TAMASSY, residing at Cleveland, in the county of Cuyahoga and State of Ohio have invented certain new and useful Improvements in Convertible Chairs, of which the following is a specification.

Our invention relates to convertible chairs, and is an improvement in that class of chairs wherein the seat and back of the chair is inverted to form a bed; all as hereinafter described and more particularly pointed out in the claims.

15 In the accompanying drawings, Figure 1 is a perspective view of the chair when folded, and Fig. 2 is a vertical section thereof showing the springs and bed mattress particularly. Fig. 3 is a vertical section on line $x-x$, Fig. 4, and Fig. 4 is a sectional view on line $y-y$, Fig. 3, showing the skeleton frame more particularly and with the upholstering, springs and mattress removed. Fig. 5 is a plan view of the frame parts unfolded for use as a bed and with the side arms lowered and broken away in part, and Fig. 6 is a longitudinal section centrally of Fig. 5.

Our invention comprises an open base frame —2— of rectangular or square formation supported by legs —3— at its four corners, and the side pieces —4— of said frame are preferably and approximately double the height of cross pieces —5—. An open seat frame —6— corresponding in size and shape to base frame —2—, is hinged at —7— to the front end of side pieces —4—, thereby permitting said seat frame to either rest flush upon base frame —2—, or be inverted 30 to the same horizontal plane at the front thereof. When inverted, cross piece —8— of seat frame —6— abuts against front cross piece —5— of base frame —2— to maintain horizontal alinement between said frames. A 35 third open frame —9— hinged at —10— to seat frame —6— is adapted to rest within a slightly larger open frame 11 which is hinged at —12— to the rear part of base frame —2—, and both frames —9— and 40 —11—, respectively, are adapted to stand upright in more or less parallel relationship to jointly form the back of the chair. To distinguish between these two back

frames, frame 9 will be hereinafter referred to as the seat back, and frame —11— as the back rest.

Seat frame —6— is inverted by tilting seat back —9— forward on its hinges —10— and then pulling it forward to cause seat frame —6— to unfold on its hinges —7— until both parts are brought to the same horizontal plane as shown in Fig. 6. In so doing a pair of legs —13— pivotally mounted in side recesses —14— on seat back —9— are caused to drop by gravity to a vertical supporting position for seat back —9—, and a similar pair of legs (not shown) may be used fore seat frame —6— if desired, but the shouldered joint at hinges —10— is deemed sufficient to produce a rigid supporting frame for the purposes required.

Hinged back rest —11— is adjustably supported at different inclinations by a curved ratchet link —15— pivotally secured to cross piece —16— of the rest frame, and which link is adapted to lockingly engage slotted keeper —17— fastened to the rear face of cross piece —5— of base frame —2—. A cable —18— attached to link —15— extends to an operating lever —19— pivotally mounted to the upper cross piece —20— of back rest —11—, and which lever is provided with a button or stem —21— adapted to project through an opening in said cross piece and where it may be engaged and depressed by the finger or hand to lift link —15— free of keeper —17— and permit raising or lowering of back rest —11— to any desired inclination. Link —15— may either lock by gravity or be spring pressed to the same end.

A further feature of the invention is embodied in the drop side arms —22— which are hinged to frame —2— at —23— at either side thereof, and which are lowered to a horizontal plane when the parts are unfolded to form a bed. Thus, each arm —22— is preferably smooth and plain its full height and length on the inside face thereof, where it abuts and rests flush against the sides of the frame parts, so that when said arms are lowered each may provide a table or stand at either side of the bed at the head thereof. In addition, the lowering of said side arms permits greater freedom for the occupant of the bed and if

no other advantage were afforded by their use, this alone would be noteworthy.

Lowering and raising of arms —22— is obtained by a pair of cables 24 and 25, respectively, a set for each at either side of base frame —2—. Each cable —24— connects with a right angled projection —27— rigidly affixed to each arm —22— and extending downwardly and inwardly beneath hinges —23—, there being an opening —28— provided therefor at the bottom of side pieces —4—. The other end of each cable —24— after passing over a sheave —29— is attached at points —30— on the inside of seat frame —6— and relatively near to the pivotal point of hinge —7— so that when seat frame 6 is inverted, cable —24— will be drawn forward and exert a like measure of pull and movement to 20 projections —27— to lower side arms —22—. However, this lowering of the side arms is not immediate, there being a relatively greater and faster movement of seat frame 6 at its free end than where cable —24— 25 is attached at point —30—, and the natural slack in the cable must also be taken up before an actual pull is had upon projections —28—. This gives an interval of rest for the side arms during initial unfolding 30 of seat frame —6—, which is taken advantage of to disengage two locking hook members —31— and —32—, mounted on seat frame —6— and side arms —22—, respectively, see Fig. 3. Said hooks pivotally 35 lock the side arms to the seat frame when the parts are folded for use as a chair. Otherwise, any outward pressure upon the arms would strain the cables and their connections. The lifting cables —25— also 40 connect with projections —27— and pass over sheaves —33— and —34— before attaching with seat frame —6— at corners —35—, and sheaves —33— are located immediately beneath projections —27— to 45 provide for a downward pull of the cables to lift arms —22—. Obviously, when cables —24— are under tension to lower arms —22—, cables —25— are slackened, and vice versa.

Now referring to Fig. 2, seat frame 6 and its extension —9— is therein shown as provided with suitable upholstering —36— on one side to provide a cushioned and finished seat and back for the chair, and coiled 55 springs 37 are also provided in both said parts, as well as base frame —2—, to not only form a yielding and comfortable chair seat but also a spring bed bottom when the chair is unfolded for sleeping or reclining 60 purposes. A hair, felt, or cotton mattress —37— or other bed clothing is also adapted to be folded and unfolded with said parts, there being sufficient space reserved for this purpose between the folding frames; 65 and one end of mattress —38— is prefer-

ably secured in any suitable manner to cross piece —20— of back rest —11— whereby when the back rest is lowered, said mattress will provide a head rest for the occupant of the bed or support pillows for this purpose.

What we claim is:

1. In a convertible chair, a base frame having an invertible seat frame hinged thereto at its front and drop arms hinged at its sides, a seat back hinged to said seat frame to unfold therewith, and means operatively connecting said seat frame and drop arms adapted to lower and raise said arms when said seat frame is unfolded and folded. 70

2. In a convertible chair, a base frame having a seat frame hinged thereto at its front and drop arms hinged thereto at its sides, and means mounted upon said base frame and operatively connected with said seat frame and drop arms, respectively, and adapted to lower said arms to a horizontal plane at the sides of said base frame when said seat frame is inverted to a horizontal plane at the front of said base frame. 85

3. In a convertible chair, a base frame having a seat frame hinged thereto at its front and drop arms hinged thereto at its sides, operating connections between said seat frame and arms adapted to lower said arms when said seat frame is inverted, and locking means to hold said arms rigid when in raised position and adapted to unlock when said seat frame is unfolded. 95

4. In a convertible chair, a base frame having a seat frame hinged thereto at its front and drop arms hinged thereto at its sides, interlocking members on said arms and seat frame adapted to rigidly support said arms when the seat frame is folded, 100 and means operatively connecting said seat frame and arms adapted to fold and unfold the same jointly.

5. In a convertible chair, a base frame having a seat frame pivotally connected therewith and provided with folding side arms adapted to be raised and lowered, and a seat back pivotally connected to said seat frame, in combination with a set of cable connections between said arms and seat frame adapted to jointly fold and unfold the same. 110

6. In a convertible chair, a base frame having an invertible seat frame and drop arms and back rest hinged thereto at its front, sides, and rear, respectively, and said seat frame having a seat back hinged thereto at its free end, in combination with means to operatively connect said seat frame and side arms to fold and unfold jointly. 120

7. In a convertible chair, a base frame having an invertible seat frame and drop arms and back rest hinged thereto, and said seat frame having a seat back hinged thereto at its free end, in combination with means 130

to fold and unfold said seat frame and arms jointly, and means to adjustably support said back rest at different inclinations.

8. In a convertible chair, a base frame having an invertible seat frame and drop arms and back rest hinged thereto, and a seat back hinged to said seat frame, in combination with means to lock said seat frame and arms together when folded, means to fold and unfold said seat frame and arms

together, and means to adjustably support said hinged back rest upon said base frame.

In testimony whereof we affix our signatures in presence of two witnesses.
